ATTORNEY

UNITED STATES PATENT OFFICE.

JOSEPH J. BOHOOCK, YONKERS, NEW YORK, ASSIGNOR, BY DIRECT AND MESNE ASSIGNMENTS, OF THIRTY-FIVE PER CENT TO CORNELIUS KYFF AND THIRTY PER CENT TO ANDREW PURCELL, BOTH OF YONKERS, NEW YORK.

COLOR BOX.

Application filed April 18, 1922. Serial No. 554,726.

To all whom it may concern:

Be it known that I, JOSEPH J. BOHOOCK, a citizen of the United States, residing at Yonkers, in the county of Westchester and State of New York, have invented certain new and useful Improvements in Color Boxes, of which the following is a specification.

This invention relates to color boxes used 10 in conjunction with multi-color printing machines, the main object being the provision of a box in which all the members are easily removable.

Another object is to provide a means for 15 preventing the leakage of the printing fluid from the sides of the color box.

Still another object is the provision of a box positive and clean in operation, simple in design, of least number of working parts 20 and comparatively inexpensive in cost of manufacture.

These and other objects will become apparent in the description below in which characters of reference refer to like-named 25 parts in the drawing.

Referring briefly to the drawing, Figure 1 represents a top plan view of the color box and illustrates the vertical guides for the printing roller.

Figure 2 is a side elevational view of the 30 same and is partly cut away to expose the interior mechanism.

Figure 3 is an elevational view partly in section on the line 3—3 of Figure 1.

Figure 4 is a side elevational view of the 35 pivot rod for the printing wheel cleaner brushes.

Describing the drawing in detail, the numeral 10 represents the side walls and 11 40 the end walls of a substantially rectangular box which is provided with a bottom 12. The enclosed chamber 13 formed by said walls and bottom generally contains a printing ink or fluid usually of the slow flowing type and of relatively high viscosity. The 45 upper portions of end walls 11 have projecting peaks 14. Said peaked portions are provided with leak-proof covers 15.

SLOTS 16 formed centrally in side walls 10 50 loosely receive the shaft 17 of a flanged inking roller 18. Said shaft is revolvably mounted in upright bearing plates 19 which

are vertically movable in the recesses of the guide bars 20, the latter being secured to the side walls 10.

Pivot bars 21 pass thru side walls 10 on opposite sides of the inking roller 18 and have a flat head at one end thereof. Said bars span the chamber 13 and are retained on the box by cotter pins 22.

Each of said bars 21 pivotally receives a cleaner brush 23 the upper end of which has follower lugs 24 contacting on the periphery 25 of the roller 18 the central flange 26 of the latter rotating between said 65 lugs 24. Said cleaner brushes 23 are kept in resilient contact with the inking roller 18 by the springs which seat upon surface 14 and are wound about the pivot rod 21 in the manner shown in Figure 1.

The color box in use, is usually secured to a table or moving part which is subjected to a linear travel and comes to an abrupt stop at the end of said travel. At this interval there is a tendency of the printing 75 fluid within the box to overflow or spill at the peaked ends, due to the inertia of said fluid. The baffle covers 15 are primarily designed to prevent this by obviously stopping the surging fluid and baffling same so 80 that it immediately flows to the rest position.

In use the roller 18 passes beneath the type cylinder and contacts with the latter. In so doing said roller is caused to rotate carrying with it a supply of printing fluid which adheres to the flanged periphery thereof. Said printing ink or fluid is distributed evenly over the surface of the roller by the 85 cleaner brushes 23.

I claim:—

1. A device of the class described comprising a box member receptive of a printing fluid and adapted to be secured to a reciprocating table of a printing machine, 95 peaked ends on said box, a baffle cover formed on said ends, the latter adapted to prevent the overflow of fluid when the box comes to an abrupt stop, vertical slots in said box, guide members within the box, 100 plates slidable between said guide members, a shaft rotatable in said plates, an inking roller on said shaft and adapted to dip into the fluid, and means resiliently contacting

with said roller on opposite sides thereof for evenly distributing the fluid over said roller.

2. A device of the class described comprising a box member receptive of a printing fluid and having vertical slots therein, guide members within the box, plates slideable between said guide members, a shaft rotatable in said plates, an inking roller on said shaft and adapted to dip into the writ-

ing fluid, cleaner brushes pivotally mounted in said box engaging the periphery of the printing roller, springs retaining said cleaner brushes in contact with the periphery of said printing roller and means for preventing the overflow of the printing fluid when said box is brought to an abrupt stop. 15

In witness whereof I, affix my signature.

JOSEPH J. BOHOCK.
